(57) **CLAIM**

The ornamental design for a case with battery charger for electric toothbrush, as shown and described.

DESCRIPTION

FIG. 1 is a perspective front view of a case with battery charger for electric toothbrush according to a first embodiment of the new design, with a translucent cover shown in a closed configuration;

FIG. 2 is a perspective rear view of a case with battery charger for electric toothbrush according to the first embodiment of the new design, with the translucent cover shown in the closed configuration;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a perspective front view of a case with battery charger tbr electric toothbrush according to the first embodiment of the new design, with the translucent cover shown in an open configuration;

FIG. 10 is a perspective rear view of a case with battery charger for electric toothbrush according to the first embodiment of the new design, with the translucent cover shown in the open configuration;

FIG. 11 is a front view thereof;

FIG. 12 is a rear view thereof;

FIG. 13 is a top view thereof;

FIG. 14 is a bottom view thereof;

FIG. 15 is a right side view thereof; and,

FIG. 16 is a left side view thereof.

All broken lines shown in the drawings are for environmental purposes only and form no part of the claimed design.

1 Claim, 14 Drawing Sheets
